(57) **CLAIM**

A new original design for a connector for use in building construction, as shown and described herein.

DESCRIPTION

FIG. 1 is a front perspective view of a connector for use in building construction;

FIG. 2 is a left side view of the connector of FIG. 1;

FIG. 3 is a perspective view of the connector of FIG. 1 from above;

FIG. 4 is an underneath perspective view of the connector of FIG. 1; and,

FIG. 5 is a front view of the connector of FIG. 1.

The right side view of the connector is a mirror image of the left side view thereof.
